UNITED STATES PATENT OFFICE.

JULIAN KENNEDY, OF PITTSBURG, PENNSYLVANIA.

ADJUSTING MECHANISM.

SPECIFICATION forming part of Letters Patent No. 634,088, dated October 3, 1899.

Application filed September 13, 1898. Serial No. 690,859. (No model.)

To all whom it may concern:

Be it known that I, JULIAN KENNEDY, of Pittsburgh, in the county of Allegheny and State of Pennsylvania, have invented a new 5 and useful Improvement in Adjusting Mechanism, of which the following is a full, clear, and exact description, reference being had to the accompanying drawings, in which—

Figure 1 shows, in partial vertical section, 10 the housings, rolls, and adjusting mechanism of a set of rolls embodying my invention. Fig. 2 is a horizontal section on the line II II of Fig. 1. Fig. 3 is a detail view of a part.

In the drawings, 2 represents the housings, 15 and 3 3' are the rolls of a rolling-mill, the upper roll 3 being vertically movable with its bearings 4 and being provided with any of the usual type of counterbalancing mechanism 5, which overbalances the roll and lifts 20 it upwardly.

6 is a hydraulic cylinder, which is shown in the drawings as being double-acting, having inlet-ports 6' above as well as below the piston and having its piston 7 connected to a cross-head 8. This cross-head carries at its 25 ends sleeves 9 9, fitting around the necks of screws 10 10 and provided with bearing-disks 11, which bear against disks 12, keyed to the shafts, and having intermediate antifriction- 30 rollers 13, so as to permit free rotation of the necks of the screws within the sleeves. The screws pass through fixed nuts 14 in the housings, and at their ends have conical heads 15, which bear against correspondingly-shaped 35 seats 16 on the roll-bearings 4, the construction being such that if these parts are forced together, as hereinbelow explained, they will bind with a clutch action, so as to prevent rotation of the screws. In order to insure 40 synchronous rotation of the screws, they are connected by gear-wheels 17 18.

On the cross-head 8 are hydraulic cylinders or other suitable motors 19, having plungers and connecting-rods 20, extending to the cross-bar 21, which connects the bearings 4. These 45 cylinders are double-acting and differential, a constant water-pressure from lower inlet-ports tending to force the plungers upwardly, and thus to lift the bearings 4, so as (by pressure of the conical surfaces 16 against the 50 ends of the screws) to lock the screws from rotation, while water admitted through upper

valve-controlled water-ports and acting on a large portion of the plungers can be employed to force the bearings 4 downwardly and to 55 free the same from frictional locking contact with the ends of the screws.

The cylinders 19 are supplied with water by telescopic pipe connections 22 23, one of which feeds the upper ports while the other 60 feeds the lower ports of the cylinders, both being adapted to maintain means of communication of the ports with the water-supply in every position of the cross-head 8.

The operation is as follows: When it is desired to vary the adjustment of the roll 3—say upwardly—the operator by manipulation of appropriate valves admits water to the lower port of the cylinder 6 and the upper ports of the cylinders 19, the valves being arranged 70 so that the cylinders 19 shall operate slightly in advance of any operation of the cylinder 6. This operation of the cylinders 19 frees the lower ends of the screws 10 from locking engagement with the bearings, leaving the 75 screws free to rotate, and the cylinder 6 lifts the cross-head 8 and the screws 10, which are carried thereby. This lifting of the screws, the threads of which are of sufficiently quick pitch to insure their angle being above that 80 of friction, causes them to rotate freely in the nuts 14, the connecting-gearing 17 18 meanwhile insuring their entire uniformity of action. During the upward motion of the cross-head the roll 3 follows it, being raised by the 85 counterbalancing mechanism 5 and the connecting-rods 20. When the proper adjustment of the roll 3 has been reached, the operator shuts off the water from the cylinder 6 and immediately thereafter exhausts the water 90 from the upper ports of the cylinders 19. The elevation of the cross-head then ceases, and the rods 20 being raised by the reverse action of the cylinders 19 the bearing-surfaces 95 16 are brought into contact with the conical heads of the screws, and by friction thereupon the screws are locked from rotation. The roll-bearings are thus held fixedly in their desired adjustment. The intensity of the locking action of the conical clutch-bearings 15 16 is increased and rendered more secure as the work on the rolls increases, for the upward pressure of the metal piece in the 100 operation of rolling causes these parts to bind

more firmly. The downward adjustment of the rolls is accomplished in like manner, the clutch-bearings 16 being first disengaged from the screws by down motion of the plungers 20, the roll-bearings being forced down by the cylinder 6 and being followed by the screws 10, which rotate in their nuts 14. When the proper adjustment is reached, the action of the cylinder 6 is stopped, and by the operation of the cylinders 19 the cross-bar 21 is lifted slightly, so as to cause the screws 10 to be locked by the pressure against them of the bearing-surfaces 16. The adjustment of the rolls in either direction is thus performed very rapidly and easily, the vertical motion of the roll-bearings being effected by the operation of the motor 6 transmitted to the bearings directly—*i. e.*, not through the screws—while the screws, moving at that time without doing any work, rotate freely in the nuts. The screws serve to hold and lock the bearings in the desired adjustment as soon as the bearings are pressed against them by operation of the auxiliary cylinders. The advantages which I obtain from this are very important. Wear on the adjusting-screws and loss of power are avoided, the adjustment is effected with great rapidity, and instead of requiring cylinders of very long stroke (as where the roll-bearings are adjusted directly by screws, which sometimes require such motors of such long range of action as to render the employment of cylinders impracticable) the work can be accomplished with cylinders or motors of convenient size and short stroke.

The operating-valves by which the cylinders are controlled may be connected in any suitable way. A convenient arrangement is shown in Fig. 1, in which the valve 24, connected with the telescopic pipe 23, is operated by the lever 25 of the valve 26, by which the upper and lower ports of the cylinder 6 are controlled. The plunger 27 of the valve 26 is connected directly to the lever 25, while the plunger of the valve 24 is connected therewith by an intermediate cam 28, the construction of which is shown in Fig. 1. This cam is so timed that the valve 24 is actuated to admit water to the cylinders 19 to unlock the screws immediately before water is admitted to either port of the cylinder 6 by means of the valve 26 for the purpose of moving the rolls vertically.

In Fig. 3 I show an improvement which I have devised for taking up loose motion on the screws in the event of wear of the threads. For this purpose I employ at the end of the nuts 14 other nuts 29, which fit on the threads of the screws and may be provided with ball-bearings 30 to permit them to rotate freely, and I provide said nuts with springs 31, which act upon the nuts through connecting-rods 32 and exert thereon a constant tension, tending to turn the said nuts and to raise the screws. The springs are sufficiently powerful to exert enough lifting force to counter-balance the weight of the screws and their

attachments. A constant bearing of the threads of the screws against the threads of these nuts 14 29 is thus preserved and the evils of lost motion are prevented.

I claim—

1. Adjusting mechanism comprising a part to be adjusted, a screw arranged to follow the said part, a motor connected to the part independently of the screw, and locking mechanism arranged to hold the screw from rotation when adjusted; substantially as described.

2. Adjusting mechanism comprising a part to be adjusted, a screw of high pitch arranged to follow the said part, a motor connected to the part independently of the screw and arranged to move the same, a nut engaged by the screw and locking mechanism arranged to hold the screw in adjusted position; substantially as described.

3. Adjusting mechanism having a motor which acts to move the parts to be adjusted, a screw adapted to follow the same, and locking mechanism adapted to hold the screw from rotation when adjustment has been effected, said locking mechanism comprising a clutch operated by vertical pressure, whereby the locking effect is increased as the work of the rolls increases; substantially as described.

4. Roll-adjusting mechanism comprising a screw of high pitch, a motor having a loose connection with the screw and arranged to move the same by endwise force, and a nut in the housing in which the screw moves; substantially as described.

5. Roll-adjusting mechanism comprising a vertically-acting motor, a screw of high pitch, a cross-head connecting the same to the motor, a nut in the housing in which the screw moves, and clutch-bearings between the screw and the roll-bearing, substantially as described.

6. Roll-adjusting mechanism comprising a lifting-motor, a screw of high pitch, a cross-head connecting the same to the motor, and a nut in the housing in which the screw moves, clutch-bearing for locking the screw, and motors on the cross-head connected with the clutch-bearings and adapted to free the same; substantially as described.

7. Roll-adjusting mechanism comprising a lifting-motor, a screw of high pitch, a cross-head connecting the same to the motor, and a nut in the housing in which the screw moves, clutch-bearing for locking the screw, and motors on the cross-head connected with the clutch-bearings and adapted to free the same, said motors comprising fluid-operated cylinders and valve mechanism whereby the same are operated successively; substantially as described.

8. Adjusting mechanism comprising a screw of high pitch, a collar in which the screw is free to rotate, mechanism for moving the collar longitudinally of the axis of the screw, and a nut engaging the screw; substantially as described.

9. Adjusting mechanism comprising screws of high pitch, collars in which the screws are free to rotate, mechanism for moving the collars longitudinally of the axes of the screws, 5 nuts engaging the screws, and connecting-gearing for the screws arranged to secure their synchronous action; substantially as described.

10. In roll-adjusting mechanism, a vertical screw of high pitch, a nut within which it turns, a second nut on the screw, and spring mechanism acting on the second nut and arranged to turn the same and to exert on the screw a lifting force, said spring mechanism 15 being sufficiently powerful to counterbalance

the weight of the screw; substantially as described.

11. In roll-adjusting mechanism, a bearing, a screw arranged to hold the bearing in its adjusted position, mechanism connected to 20 the bearing independently of the screw and arranged to move the bearing, and mechanism for moving the screw longitudinally of its axis; substantially as described.

In testimony whereof I have hereunto set 25 my hand.

JULIAN KENNEDY.
